UNITED STATES PATENT OFFICE

JEROME R. GEORGE, OF WORCESTER, MASSACHUSETTS, ASSIGNOR TO MORGAN CONSTRUCTION COMPANY, A CORPORATION OF MASSACHUSETTS.

GUIDE FOR ROLLING MILLS

Application filed March 26, 1928. Serial No. 264,586.

The present invention relates in general to the guide devices used in rolling mills, and more particularly contemplates an improved construction for a delivery guide.

5. Rolling mill delivery guides of ordinary construction provide more or less elongated interior guide surfaces for close engagement with the top, bottom and sides of the rolled product as it emerges longitudinally from the pass of a stand of reducing rolls, — thus overcoming any tendency of the product to be deflected from its path of travel to the next reducing pass of the mill.

Delivery guides so constructed, while offering considerable frictional resistance to the longitudinal movement of the product, are nevertheless quite satisfactory in operation when an elongated piece is being rolled, because such a piece will run out far enough 10 beyond the delivery guide, before its last end leaves the reducing rolls, to give opportunity to the conveyor rolls beyond said guide to pull said last end through said guide. However, in the rolling of short pieces and particularly those of relatively large cross section, a delivery guide of this ordinary construction operates at a serious disadvantage, because the power required to pull the last end of such a piece through the guide cannot be obtained 15 when there is only a short projection of the piece on the conveyor rolls in front of the guide.

The present invention contemplates a delivery guide construction which obviates this difficulty, by the provision within said guide of a power driven roller adapted to engage with and impart longitudinal movement to the piece, thus insuring invariably the latter's prompt emergence from the guide, as soon as 20 its last end has been released by the reducing rolls. The various features of the invention are fully set forth herein, reference being had to the accompanying drawings, in which—

45 Fig. 1 is a diagrammatic plan view of rolling mill apparatus, showing the application of my invention thereto.

Fig. 2 is a sectional view of the apparatus shown in Fig. 1.

50 Fig. 3 is a fragmentary large scale sec-

tional view on the line 3—3 of Fig. 2, showing how the bar or piece of stock is guided.

Fig. 4 is a view similar to Fig. 3, showing a slightly modified construction.

Like reference characters refer to like parts in the different figures.

In the drawings, I have shown by way of example a stand of reducing rolls 1, 1 of ordinary construction, arranged to deliver the hot rolled product longitudinally onto a series of conveyor rollers 2, 2, which forward the stock in the usual manner to another stand of reducing rolls 3, 3, for further reduction in its passage therebetween. A delivery guide, designated as a whole by the numeral 4, is secured in any suitable manner to, and projects forwardly of, the housing of the reducing rolls 1, 1, — the forward projection of this guide being sufficient in all cases to maintain correct axial alinement of the stock with the series of conveyor rollers 2, 2 and with the pass of the reducing rolls 3, 3. Said conveyor rollers 2, 2 which receive the stock from the delivery guide 4 are driven in any suitable manner, as by gearing 5, 5 from a common drive shaft 6, and it is to be noted that the arrangement of apparatus described above meets the requirements of the ordinary situation in a rolling mill, provided always that the pieces of stock emerging from the reducing rolls 1, 1 are long enough to project their forward ends well beyond the guide 4 before their rear ends leave the pass of said rolls 1, 1.

The delivery guide device of the present invention, however, embodies a special construction to meet a different situation, viz., one where the pieces of stock emerging from the reducing rolls 1, 1 are relatively short and hence are apt to become stuck in the delivery guide after their last ends have been released by the reducing rolls 1, 1. In such a situation, one delivery guide section, here shown as the upper section 7, that is adjusted by the usual wedge 7', is in such a form as to provide interior guiding surfaces of the usual length for contact with the top and sides of the stock; but the other guide section, here shown as the lower section 8, carried by the housing bar 9, is so formed that its interior guid-

ing surface has only a relatively short forward projection from the reducing pass, instead of extending, as usual, for the full length of the guide. This construction permits a roller 10 to be incorporated within the length of the guide, said roller having its axis at right angles to the direction of travel of the stock in the guide. Said roller 10 is so journaled either in the guide itself, or independently thereof as shown, as to contact on its periphery with said stock, thereby to move it longitudinally, due to rotation of said roller 10 in the same direction as conveyor rollers 2, 2, through the medium of gearing 11 from the shaft 6. In this way, without any sacrifice of accuracy in guiding, pieces of stock so short that they would become stuck in any ordinary delivery guide, are readily handled in and promptly discharged from the guide, by the forward motion imparted to said pieces by the driven roller 10. In addition, the incorporation of this roller 10 in the guide lessens the danger of a piece jamming therein, as sometimes happens when the adjustment of the guide, to the line of the pass or to the section of the stock, is faulty. And if a "cobble" does occur, the guide can be freed much more readily than an ordinary guide because of the better access afforded to its interior from its outer end.

As shown in Fig. 3, the presence of the roller 10 prevents the hot billet or bloom from bending down, notwithstanding the absence of support therefor which results from the omission to extend outwardly the lower section 8 of the guide. The same is true of the modified form of roller designated at 12 in Fig. 4, and having a peripheral groove 13 to receive the lower corner of the billet or bloom, thereby to eliminate the possibility of any twisting. In both forms, the cooperation existing between the driven roller, incorporated in the guide, and the stationary guide sections 7 and 8 serves to confine the billet or bloom laterally in every direction while at the same time leaving it free to be moved longitudinally by said roller, as soon as released by the reducing rolls. In other words, the use of such a roller makes it possible to employ a guide that is long enough to hold the billet straight, and that still does not have to fit the billet with undue closeness.

With the driven guide roller supported, as shown, independently of the other members of the guide structure, the vertical adjustment of the lower roll of the stand of rolls 1, 1, by any suitable adjusting means 14, maintains the correct alinement between the reducing pass and the surface of said driven guide roller. However, my invention is not limited to such independent support of the driven guide roller, but what I claim and desire to secure by Letters Patent of the United States is as follows:—

1. The combination with a stand of reducing rolls of a rolling mill and a delivery guide adjacent the discharge side of the pass between said rolls, to engage with and maintain the direction of the rolled product as it emerges from said pass, said guide having incorporated therewith, in close proximity to said pass, a driven roller to procure the discharge of the rolled product from said guide, after said reducing rolls are no longer effective to impart movement to the last end of said product. 70

2. In a delivery guide for rolling mills, a relatively elongated portion providing interior guide surfaces to engage and maintain the direction of the rolled product as it emerges from the reducing pass between a pair of rolls, a shorter portion opposing said elongated portion, and a driven roller supplementing said shorter portion and adapted, 80 by engagement with said rolled product, to insure the latter's discharge from said guide, following the emergence of the last end of said rolled product from the reducing pass. 85

3. In a delivery guide for rolling mills, a relatively elongated portion providing interior guide surfaces to engage and maintain the direction of the rolled product as it emerges from the reducing pass between a pair of rolls, a shorter portion opposing said elongated portion, and a driven roller supplementing said shorter portion and adapted, 90 by engagement with said rolled product, to insure the latter's discharge from said guide, following the emergence of the last end of said rolled product from the reducing pass, the axis of said roller being at right angles to the line of movement of the stock through said guide, and said roller cooperating with said guide portions to maintain the rolled product in its line of delivery, in the absence of any twisting or lateral deflection. 95

4. The combination with a stand of reducing rolls, of a delivery guide therefor having incorporated therein a driven roller to engage and forward the rolled product after the last end of the latter has cleared said rolls, and means for vertically adjusting the lower roll of said stand, to maintain alinement between the reducing pass and said driven guide roller. 100

5. The combination with a stand of reducing rolls, of a series of conveyor rollers to receive the rolled product from said reducing rolls, and a delivery guide interposed between said reducing rolls and said conveyor rolls, said delivery guide having incorporated therein a driven roller to engage and forward the last end of the rolled product, when the latter has cleared said reducing rolls. 110

6. The combination with a stand of reducing rolls, of a series of conveyor rollers to receive the rolled product from said reducing rolls, a delivery guide interposed between said reducing rolls and said conveyor rolls, 115

said delivery guide having incorporated therein a roller to engage and forward the last end of the rolled product, when the latter has cleared the reducing rolls, and common driving means for said conveyor rolls and
5 said guide roller.

Dated this 13th day of March, 1928.
